SUSPENDABLE COMBINED TABLE
AND CHANDELIER

Jannette C. Olinger, 4912 N. Sipple,
Spokane, Wash. 99206

Filed Oct. 13, 1971, Ser. No. 189,074

Term of patent 14 years

Int. Cl. D6—03

U.S. Cl. D6—113

FIG. 1

FIG. 2

FIG. 1 is a perspective view from above of a suspendable combined table and chandelier showing my new design; with one leaf removed for illustrative purposes; and

FIG. 2 is a perspective view from below.

I claim:

The ornamental design for a suspendable combined table and chandelier, substantially as shown and described.
